UNITED STATES PATENT OFFICE

164,156

HOBBYHORSE

Stella Chenault, Sadie Chenault, and Birdie
Chenault, Berkeley, Calif.

Application June 15, 1950, Serial No. 10,545

Term of patent 7 years

(Cl. D34—15)

To all whom it may concern:

Be it known that we, Stella Chenault, Sadie Chenault, and Birdie Chenault, each a citizen of the United States of America, residing at Berkeley, in the county of Alameda, and State of California, have invented, as joint inventors, a new, original, and ornamental Design for a Hobbyhorse, of which the following is a specification, reference being had to the accompanying drawing, forming part thereof.

Fig. 1 is a side elevation of a hobbyhorse showing our new design.

Fig. 2 is a top plan view of the hobbyhorse shown in Fig. 1.

Fig. 3 is a bottom plan view of the hobbyhorse shown in Fig. 1.

We claim:

The ornamental design for a hobbyhorse, as shown.

STELLA CHENAULT.
SADIE CHENAULT.
BIRDIE CHENAULT.
